THOMAS S. HOMANS, OF HEMPSTEAD, NEW YORK, ASSIGNOR TO INTERNATIONAL TYPESETTING MACHINE COMPANY, OF NEW YORK, N. Y., A CORPORATION OF NEW YORK.

LINOTYPE-MACHINE.

1,130,600.

Specification of Letters Patent.

Patented Mar. 2, 1915.

Application filed July 25, 1912. Serial No. 711,516.

To all whom it may concern:

Be it known that I, THOMAS S. HOMANS, a citizen of the United States, residing at Hempstead, in the county of Nassau and State of New York, have invented new and useful Improvements in Linotype-Machines, of which the following is a specification.

The present invention relates to improvements in linotype machines, and the primary object of the invention is to provide improvements in assembling elevators of the type adapted to receive and assemble at different levels matrices bearing two or more characters, the rail for supporting the matrices at the upper level, according to the present invention, being continuous or free from joints or interruptions, thereby avoiding the presence of shoulders or obstructions which would be liable to retard or arrest the movement of the matrices and thus interfere with the assembling of a line.

Modern linotype machines use matrices each bearing a plurality of characters, two characters being most generally used on each matrix, and such characters are assembled at different levels in order to bring the character to be used into correct alinement preparatory to the transfer of the line to the casting mechanism. In linotype machines employing multiple letter matrices, it is customary to make the assembling elevator with stationary rails to support the matrices at the lower level and to provide an upper rail to support or position the matrices at the upper level, and such upper rail is usually made of two parts, the part nearer to the receiving end being relatively short and is arranged to be withdrawn in order to permit the incoming matrices to drop past the upper rail to the lower rail. Experience has shown that a shoulder develops between the two sections of the upper rail due to wear or other causes, and such shoulder obstructs the matrices while passing between the two parts of the upper rail, thus interfering with the assembling of the matrices. In the preferred embodiment of the present invention, this upper rail is made in one piece and embodies a strip of yieldable or resilient material which provides a continuous or uninterrupted surface from end to end for engagement of the matrices, that portion of the strip adjacent to the matrix-receiving end of the elevator being movable to and from an operative position, and preferably such end of the strip has a tendency to

spring out of the path of the incoming matrices, means being provided for forcing this end of the strip composing the rail into the path of the matrices when it is desired to assemble the matrices on the upper rail.

To these and other ends, the invention consists in certain improvements, and combinations and arrangements of parts, all as will be hereinafter more fully described, the novel features being pointed out particularly in the claims at the end of the specification.

In the accompanying drawings:—Figure 1 is a perspective view of the upper portion of the assembling elevator of a linotype machine embodying the present invention, the elevator being viewed from the rear; Fig. 2 is a rear view of the elevator showing the back thereof removed; Fig. 3 represents an end view of the elevator looking toward the matrix-receiving end thereof.

Similar parts are designated by the same reference characters in the several views.

The preferred embodiment of the invention is shown in the accompanying drawing and will be hereinafter described in detail, although it will be understood that the invention in its broadest sense is not restricted to the particular construction shown, as equivalent constructions may be used to produce the same results.

In the present instance, 1 and 2 designate the front and rear side members of the assembling elevator as usually employed on linotype machines, the matrices X being fed to the receiving end of the elevator, after being delivered from the magazine by manipulation of the keyboard, by the usual traveling belt 3 passing over the pulley 4, and the star wheel 5, the latter being arranged at the entrance to the elevator. The members 1 and 2 of the elevator are provided as usual with the oppositely positioned lower rails 6 and 7 which serve to support the matrices at the lower level, as shown diagrammatically in Figs. 2 and 3. The member 1 of the elevator is shown provided with the usual hinged section 8 which may be swung forward by the operator when it is desirable or necessary to remove or insert matrices for the purposes of making corrections by hand. The forward or receiving end of the hinged section 8 is shown provided with the usual detent 9 to prevent retrograde movement of the matrices as they enter the elevator, a similar oppositely positioned detent 10 being shown on the upper

edge of the elevator member 2 for the same purpose.

The upper rail which serves to support or position the matrices at the upper level embodies, in the present instance, a strip 11, the inner edge of which projects into the passageway for the matrices, and the major portion of this strip beyond the matrix-receiving end of the elevator is secured in 5 fixed position by a bar or clamp 12 which is secured to the body portion of the elevator member 1 by the screws 13. That portion 14 of the strip adjacent to the matrix-receiving end of the elevator is bendable 10 or yieldable or otherwise movable in a manner which enables it to move to and from a position to engage and receive the incoming matrices at the upper level or to clear the incoming matrices and permit them to 15 assemble on the lower rails as may be desired. Preferably, the strip composing the rail is made of resilient or springy material, and the forward end 14 thereof has an inherent tendency to curl upwardly so as to 20 normally occupy substantially the position shown by the full lines in Fig. 2. While this portion 14 of the strip composing the upper rail is in this position, the incoming matrices will pass freely to the lower rails and 25 will assemble thereon. When, however, this portion of the strip composing the upper rail is flattened or straightened out so as to occupy a position in alinement with the remainder of the strip as indicated by the 30 dotted lines in Fig. 2 and the full lines in Fig. 1, the incoming matrices will then engage this end of the strip and will be thereby positioned and supported at the upper level. The clamp or bar 12 terminates short 35 of the portion 14 of the strip to permit the same to operate in the manner described. A device, however, is provided whereby the portion 14 may be flattened to bring it into 40 operative relation to the incoming matrices and may be permitted to curl or move out of 45 operative position with respect to the incoming matrices, a slide 15 being provided in the present instance which is movable longitudinally of the strip, and rectilinear 50 movement of this slide may be insured for example by providing the slide with an extension 16 which reciprocates beneath an overhanging portion 17 of the clamp 12, and a knob or handle 18 may be attached to the 55 slide to enable the operator to manipulate the slide and thereby cause the matrices to assemble at the upper or lower level at will.

I claim as my invention:—

1. In a linotype machine, an assembling 60 elevator embodying rails for supporting matrices at different levels, one of said rails having a portion bendable vertically to and from operative position to control the as-

sembling of the matrices at the different levels.

65

2. An assembling elevator for linotype machines embodying upper and lower rails for supporting matrices at different levels, the upper rail being in one piece and having its receiving end bendable vertically to and 70 from operative position to control the assembling of the matrices at the different levels.

75

3. The combination with an assembling elevator for linotype machines adapted to handle matrices having a plurality of characters, of a rail in the elevator for supporting the matrices at an upper level and embodying a continuous strip of yieldable material having its receiving end bendable to 80 and from a position to receive and support the incoming matrices whereby the latter may be assembled on or beneath said rail.

85

4. In a linotype machine and in combination with an assembling elevator for receiving and carrying matrices having a plurality of characters, a rail in said elevator for supporting the matrices in an upper position, one end of said rail having a tendency to spring out of the path of the incoming 90 matrices, and means to force said rail into the path of the incoming matrices whereby the matrices may be assembled on or under the rail at will.

95

5. In a linotype machine and in combination with an assembling elevator for receiving and carrying matrices having a plurality of characters, of a rail in said elevator for supporting the matrices in an upper position, said rail having a continuous supporting surface and being made of elastic material having an inherent tendency to curl or bend out of the path of incoming matrices, and means to force said rail into the path of the incoming matrices at will. 100

105

6. The combination with an assembling elevator for linotype machines adapted to coöperate with matrices each having a plurality of characters at different levels, of a rail in the elevator for assembling and supporting the matrices at an upper level, said rail composed of a continuous strip of resilient material, the matrix-receiving end of which has a tendency to curl upwardly and thereby permit incoming matrices to 115 assemble beneath such rail, and means for straightening such end of the strip in a manner to receive and assemble incoming matrices thereon.

110

In testimony whereof I have hereunto set 120 my hand in presence of two subscribing witnesses.
